2,596,461

SPEED RESPONSIVE VALVE FOR FUEL-
FEEDING SYSTEMS

John Carroll Baisch, Whittier, Calif., assignor to
Carter Carburetor Corporation, St. Louis, Mo.,
a corporation of Delaware

Application August 11, 1948, Serial No. 43,731

8 Claims. (Cl. 123—130)

1

This invention relates generally to fuel supply systems, and relates more particularly to such systems wherein the fuel is supplied under positive pressure.

While the invention has utility as a fuel supply system for various devices, it is particularly useful for supplying fuel to internal combustion engines, and is shown and described in such connection.

It is an object of the invention to provide a fuel supply system which will provide the proper quantity of fuel for the engine fuel mixture under various operating conditions.

It is another object of the invention to provide a device of this character wherein the metering of the fuel is controlled in accordance with engine speed and one or more other operating variables.

Still another object of the invention is to provide an arrangement of this character wherein the valve which controls the metering of the fuel is controlled by a speed responsive centrifugal device, which may be engine driven, and means responsive to one or more other operating variables.

A further object of the invention is to provide a fuel control system wherein the fuel control valve may be variously positioned relative to the position effected in accordance with engine speed.

Another object of the invention is to provide a device of this character wherein the means for varying the position of the fuel control valve relative to the position effected by engine speed may be one or more means responsive respectively to engine charging pressure, engine temperature and/or barometric pressure.

Still another object of the invention is to provide a device of this character that is simple in construction and operation.

Other objects and advantages of the invention will appear from the following part of the specification.

Referring to the drawings, which are for illustrative purposes only,

Fig. 1 is a diagrammatic view, partially in section, of a fuel supply system embodying the present invention;

Fig. 2 is a view of the outside of the piston housing as seen from the right hand side in Fig. 1;

Fig. 3 is a sectional view of an induction passage showing alternative connections for the pressure responsive device; and

Fig. 4 is a fragmentary view of means for varying the position of the metering valve in accordance with temperature and/or barometric pressure.

Referring to Fig. 1, there is shown a fuel supply

2

system wherein the fuel is supplied by a pump, indicated generally at 10. The pump may be of any well known type capable of delivering fuel at a substantially constant pressure (although it may have other delivery characteristics). Liquid fuel is supplied to the pump 10 by means of a conduit 11 connected to a suitable source of fuel, not shown, and the pump delivers the fuel through a conduit 12 which leads to a fuel nozzle in the induction passage of the engine posterior to the throttle valve. Should a supercharger be used, the conduit 12 may be connected to the intake manifold posterior to said supercharger. If desired, a pressure operable nozzle, not shown, of any well known type, may be used, adjacent the discharge end of the conduit 12, said pressure operable nozzle functioning in the well known manner. Within the conduit 12 there is disposed a calibrated restricted metering jet or orifice 13 controlled by a tapered movable valve 14 which is provided with a stem 15 slidable in a guide 16.

Means for controlling the position of the valve 14 in accordance with engine speed comprises a speed responsive centrifugal device, indicated generally at 20, and shown as comprising a fly ball governor of well known type having a rotatable shaft 21 connected to a rotating part of the engine, not shown, by any suitable well known means such as gearing or the like, also not shown. The speed responsive device 20 may rotate at engine speed or at some other speed proportional to or representative of engine speed. To the shaft 21 is fixed a member 22 which has no longitudinal movement, but which rotates the said shaft 21, said member 22 having a depending, diametrically extending part 23. As shown in the drawings, the upper ends of a pair of arms 24 are pivoted, as at 25, to the opposite sides of the part 23, said arms 24 having weights 26 adjacent their lower ends. A pair of links 27 are provided, each of which is pivoted, at 28, adjacent one end to an intermediate part of the arms 24, the opposite ends of said links being pivoted at 29 to oppositely disposed ears 30 of a member 31 having an axial bore 32 for slidable reception of a guide rod 33.

The lower end 35 of the member 31 is of larger diameter than the upper end and is externally threaded for reception of an internally threaded cap 36, there being a shoulder 37 on said enlarged part 35, against which the upper or inner end of the cap 36 abuts. The cap has an inwardly extending annular flange 40 with an axial opening 41 therein for reception of a stem 42 of a cylin-

der member 43, which will be more fully described hereinafter, said stem 42 being loosely received in said opening 41.

The cap is of such length that the flange 49 is spaced axially from the adjacent end of the member 31 to provide a chamber 44 for an enlarged diameter disc-like head 45 of the stem 42, said head being of smaller diameter than the internal diameter of the chamber 44 and being located adjacent the upper end of said stem 42.

Ball bearings 46 are disposed between the head 45 and the adjacent part 35 and also between said head and the flange 40, suitable raceways being provided in the respective parts to retain the balls 46 in place. Thus, the member 31 may rotate substantially without friction and without imparting rotation to the cylinder member 43, which is axially or longitudinally slidable within the bore 47 of a guide 48 and is held against rotation by a laterally extending tubular portion 49 slidable longitudinally in the slot 50. The guide 48 is provided with a laterally extending bracket 51 which is adapted to be secured to any convenient fixed support (not shown), whereby the guide 48 will be held in a fixed position.

The cylinder member 43 has a cylindrical bore 52 extending from the end thereof opposite the stem 42, said bore being closed at the inner end by a wall 53 from which said stem 42 projects.

The valve stem 15 is provided with a piston 54 which is slidable in the cylindrical bore 52, the latter being connected to a source of engine charging pressure by means of a passage 55 in the portion 49 and conduit 56. The conduit 56, or at least a portion thereof, is flexible to permit free sliding movement of the cylinder member 43 in the bore 47 of the guide 48. The opposite end of the conduit 56 is shown as being connected to the engine intake passage or manifold 57 posterior to the throttle valve 58 and if desired a restricted, calibrated orifice 59 is provided in the connection between the intake manifold or passage and the cylinder 52. The end portion of the cylinder 52 opposite the wall 53 has an external thread for reception of an internally threaded cap 60 which does not extend beyond the plane of the internal bore 52, so as to prevent any binding between the parts, said cap 60 having an inwardly extending flange 61 which limits outward movement of the piston 54. The cap 60 also has an axial opening 62 for the free reception of the valve stem 15.

The adjacent end of the guide also has an externally threaded portion for reception of an internally threaded cap 63 which has an end wall 64 limiting downward movement of the cylinder member 43, as shown in the drawings, said wall 64 having an axial opening 65 through which the valve stem 15 freely extends. The cap 63 is threadedly adjustable on the guide 43 so as to adjust the position of the valve 14 relative to the orifice 13. This is so that, if desired, the valve 14 may be positioned in a slightly open position for supplying idling fuel and the cap is provided with a set screw 67 for securing same in adjusted positions.

In order to maintain the valve 14 in the closed or substantially closed position when the mechanism is at rest, a spring 43a is provided in the guide 43 which reacts between an inturned abutment or flange 48a and the inner end of the cylinder member 43. It is to be understood that the flange 48a is of sufficient size to permit adequate engagement with the spring, but provides an opening in which the enlarged portion 35 of

the member 31 may freely move. Also, there is a spring 54a which reacts between the bottom wall 53 of the cylinder 52 and the piston 54.

It is also desirable to limit the inward movement of the piston 54 and means for thus limiting said movement is provided and comprises a part 53a which extends inwardly of the cylinder 52 from the wall 53 and has an internally threaded bore for reception of a screw 53b. The free end of said screw 53 is disposed in spaced relation to the piston 54 so that it will limit inward movement of said piston.

In Fig. 3 there is shown an arrangement whereby the cylinder 52 may be connected to parts of the intake passage or manifold other than as shown in Fig. 1. In Fig. 3 there is shown a large venturi 70 and a small venturi 71. The cylinder 52 may be connected with either of these venturis, as indicated at 72 and 73 respectively, and there is metering means or orifices 74 and 75 respectively in these connections.

It is to be understood that the connection between the cylinder 52 and the induction passage may be by any one of the conduits or connections disclosed herein or by means of all of them, or various combinations thereof, in accordance with requirements of various installations.

Inasmuch as it is also desirable in many types of installations to provide a temperature control of the fuel supply, such control may be effected by a temperature responsive device 77, Fig. 4, which has one end attached to the stem 15 of the valve 14 and the opposite end connected with the piston 54 by means of a stem 78.

The jet or orifice 13 and the valve 14 comprise variable metering means for controlling the flow of fuel to the engine. As is well known, the rate of liquid fuel flow through a fuel metering orifice is proportional to the square root of the pressure difference across said orifice. With an orifice of a given size, supplied with fuel at a substantially constant pressure, as by the pump 10, the supply of fuel to the engine may be varied by variously positioning the valve 14 in accordance with certain engine or operating variables.

In the present arrangement, one of these engine operating variables, provided for varying the position of the valve 14, and hence varying the effective size of the orifice, comprises the centrifugal device 20.

When the engine is inoperative, the valve 14 is in the closed position (although it may be otherwise positioned for some installations). Upon rotation of the speed responsive device 20, centrifugal force will cause the weights 26 to move outwardly and move upwardly (as shown in the drawings) the member 31, stem 42, cylinder member 43, valve stem 15, and valve 14. This movement will be effected against the force of the spring 43a, it being understood that the valve stem 15 and valve 14 will move in accordance with the movements of the member 43 due to the action of the spring 43a. Further, this movement of the valve in the opening direction will be substantially proportional to the square of engine speed because of the inherent operating characteristics of the centrifugal device which characteristics are well known.

Thus with this arrangement, the effective area of the orifice 13 is controlled substantially in proportion to the square of engine speed by means of the centrifugal governor. As the quantity of fuel which will flow through a metering orifice of a given size will vary in proportion to the square root of differential pressure across said orifice or

on opposite sides thereof, and as the size of the orifice is varied in accordance with square of engine speed, it will be apparent that the above described arrangement provides a fuel control wherein the quantity of fuel supplied to the engine through the metering jets or orifices 13 will vary directly as the engine speed. However, the valve 14 may be contoured differently from the contouring shown, to provide other metering characteristics. The means for controlling the valve 14 in accordance with engine intake passage or engine charging pressure includes the cylinder member 43 and the piston 54. The piston 54 is subjected to the engine charging pressure by reason of the conduit connection 56 with the cylinder 52. As shown in the drawings, air passes through the passage 57 from top to bottom, the air entering at the top. The induction passage 57 has its outlet connected to the engine cylinders, or to a supercharger inlet, should a supercharger be used. A supercharger might alternatively be connected to the inlet of the induction passage or there might be a supercharger connected to both the inlet and outlet. Should a supercharger be used, the conduit 56 would be connected to the engine intake manifold posterior to said supercharger.

Therefore, in view of the fact that the weight of airflow to an internal combustion engine at a given manifold pressure varies substantially in direct proportion to the speed of the engine, the device herein described will supply fuel to the engine in accordance with airflow therethrough.

Thus, when engine charging pressure is low (or the manifold vacuum high), the pressure in the cylinder 52 will be low and the differential of pressure across the piston 54 will cause said piston to move inwardly in said cylinder and increase the effective size of the metering orifice 13. Thus, it will be apparent that the valve 14 is controlled in accordance with engine charging pressure which reflects throttle pressure and engine speed and load.

Assuming that the engine is operating within its normal range, say, at a speed between idling and the power range, the piston 54 will be maintained at its outmost position by the spring 54a, it being understood that under these conditions, said spring is so calibrated that the differential of pressure across the piston 54 will be insufficient to overcome the force thereof. At this time the quantity of fluid supplied to the engine will therefore be controlled in accordance with engine speed. However, the force of the spring 54a is overcome by the differential of pressure across the piston 54 when the throttle valve is in a substantially closed or idling position, and the engine pressure is consequently relatively low. Thus, the piston 54 will be actuated to effect suitable opening of the valve 14 to enrich the mixture. The engine charging pressure is also relatively low when the engine is operating at high speed. At this time the force of resistance of the spring 54a is also overcome by the differential of pressure across the piston 54 so that the valve 14 is moved to an open position, greater than that effected by the speed responsive device, and the fuel mixture enriched as is required under such conditions.

Should the cylinder 52 be connected to either the large or small venturi, the piston 54 will be actuated in accordance with the pressure anterior to the throttle. Should both of the connections 72 and 73 be used, a similar result would be effected as modified by the action of the ven-

turis. Should either or both of the connections 72, 73 be combined with the connection 56, the former would bleed air to the cylinder 52 when the throttle valve is closed and thus modify the action of the pressure posterior to the throttle. However, when the throttle valve is opened, the pressures in either or both of the venturis and pressure posterior to the throttle would be combined to move the piston 54 inwardly.

- 10 If desired, the position of the valve 14 may be further modified by the temperature responsive device 77, which may be placed adjacent some portion of the engine so as to be subjected to the temperature thereof. Thus, when the engine is 15 cold, the bellows 77 would be contracted to a degree, depending upon the subnormal operating temperature, and thus effect a further opening of the valve 14 to enrich the mixture for cold operating conditions. As the engine warms up to 20 normal operating temperature, the bellows 77 would expand accordingly to lean the mixture as desired. It is to be understood, of course, that means may be provided for limiting expansion of the bellows should such an arrangement be found necessary.

The bellows may be of such character as to be responsive only to temperature or it may be so constructed and arranged as to be responsive to barometric pressure. Or, the bellows may be so 30 constructed and arranged in the well known manner as to be responsive to both temperature and barometric pressure.

It is to be understood, of course, that the device responsive to engine charging pressure may vary 35 the position of the valve 14 relative to the position which would otherwise be effected by the speed responsive device 20, and the same is true of the temperature responsive device 77.

While particular types of mechanisms are 40 shown herein, it is to be understood that other types of speed responsive centrifugal devices may be employed and other types of pressure responsive devices may be used. Also, other types of temperature and/or barometric responsive devices 45 may be used instead of the bellows shown in Fig. 4.

I claim:

1. In fuel control means: a fuel conduit; variable metering means for said conduit, said variable metering means including a movable valve part; a casing having a cylindrical chamber; a device slidable in said chamber and having a cylindrical bore therein; a piston in said bore, said piston being connected to said valve part; means for connecting said bore to a source of variable pressure for actuating said piston; and speed responsive means connected to said device and adapted to move same in said chamber.
2. The invention defined by claim 1 wherein 60 there is a temperature responsive device interposed between said piston and said valve part.
3. The invention defined by claim 1 wherein there is adjustable means for limiting movement of the device in one direction in said chamber.
4. The invention defined by claim 1 wherein there is adjustable means for limiting movement of the piston in one direction.
5. In a fuel control mechanism: a fuel conduit; a variable metering valve for said conduit, including a movable valve part; a casing having a cylindrical chamber; a device slidable in said chamber, said device having a cylindrical bore; a piston slidable in said bore, said piston being connected to said valve part; means for connecting said bore to a source of varying pressure for ac-

tuating said piston; yielding means urging the piston in a direction to close said valve; means limiting piston movement in said direction; yielding means urging said device in the valve closing direction; means limiting movement of said device in said direction; and speed responsive means connected to said device for moving said device in the opposite direction.

6. The invention defined by claim 5 wherein there is adjustable means limiting movement of the piston against the force of the yielding means acting on said piston.

7. The invention defined by claim 5 wherein the means limiting movement of the device in the valve closing direction comprises a cap threaded 15 to the casing for adjustably limiting the movement of said device in said direction.

8. The invention defined by claim 5 wherein the casing has a longitudinally extending slot and

said device has a laterally extending projection 5 said slot.

JOHN CARROLL BAISCH.
